(57) **CLAIM**

The ornamental design for a hose reel, substantially as shown and described.

DESCRIPTION

FIG. 1 is a perspective view, taken from the top, left and front of the new design;

FIG. 2 is a top view of the design of FIG. 1;

FIG. 3 is a left side view of the design of FIG. 1;

FIG. 4 is a front view of the design of FIG. 1;

FIG. 5 is a rear view of the design of FIG. 1;

FIG. 6 is a right side view of the design of FIG. 1; and,

FIG. 7 is a bottom view of the design of FIG. 1.

The broken lines showing environment in the drawing are for illustrative purposes only and form no part of the claimed design.
